(57) CLAIM

The ornamental design for a bag clip for a pool cleaner filter bag, substantially as shown and described.

DESCRIPTION

FIG. 1 is a perspective view showing the front, top and right sides of a bag clip for a pool cleaner filter bag embodying the new design with a fragmented portion of a filter bag assembled therewith being shown in dotted lines for illustrative purposes only and forming no part of the claimed design;

FIG. 2 is a front elevation view thereof, the rear elevation view being identical to the front elevation as shown;

FIG. 3 is a right side elevation view thereof, the left side elevation view being identical to the right side elevation as shown;

FIG. 4 is a top plan view thereof;

FIG. 5 is a bottom plan view thereof; and,

FIG. 6 is a perspective view similar to FIG. 1, but illustrating the bag clip in an open configuration.
